UNITED STATES PATENT OFFICE.

DAVID P. WHITESELL, OF GREENVILLE, OHIO.

FILM-WINDING DEVICE.

1,225,905.

Specification of Letters Patent. Patented May 15, 1917.

Application filed March 30, 1916. Serial No. 37,760.

To all whom it may concern:

Be it known that I, DAVID P. WHITESELL, a citizen of the United States, residing at Greenville, in the county of Darke and State of Ohio, have invented certain new and useful Improvements in Film-Winding Devices, of which the following is a specification.

My invention relates to new and useful improvements in film winding devices, and relates more particularly to a class in which the film is received from the projector, and is wound in a receiving member in a condition to be again run through the projector without rewinding.

An object of my invention is to provide a device of the character described wherein there is a minimum of parts and a positive feeding means for the film. An object of my device is also to so construct the several parts that the film receiver may be readily withdrawn from the device.

Another object is to provide a device of the character described wherein said device will automatically reset itself when the wound film is removed from the device.

A still further object is to provide a device wherein the receiver for the film is rotated at a continuously increasing speed, thus compensating for the constantly shortening of the winding periphery of the film receiver.

The invention resides in certain novel apparatus for accomplishing the purpose stated, the novel principles as well as the structural and co-operative features of which will be pointed out through means of a preferred embodiment selected for purposes of illustration; also in certain details of construction of the said preferred embodiment of such apparatus, all as hereinafter fully described and particularly pointed out in the claims.

In the drawings—

Figure 1 is a side elevation of my improved film winding device shown partly in section;

Fig. 2 is a top plan view;

Fig. 3 is an enlarged end view;

Fig. 4 is an enlarged detail section taken 50 on the line 4—4 of Fig. 1;

Fig. 5 is an enlarged detail section taken on the line 5—5 of Fig. 3, and

Fig. 6 is an enlarged detail section on the line 6—6 of Fig. 4.

Referring more particularly to the draw-

ings, in which like reference characters designate corresponding parts, 1 indicates a base member upon which is rotatably mounted a film receiving pan 3 in an axially yielding bearing 2. Adapted to extend diametrically across the pan 3 is a frame member 4 that supports the film feeding and guiding means which will be hereinafter more specifically described. One end of the frame member 4 is pivotally mounted upon the transverse shaft 5 supported in the bearings 6 of the standards 7 which have their lower extremities connected by a sub-base member 8, adapted to be secured to the base. The other end of the frame member 4 is removably secured to the standard 9 by means of the wing nut 10 and the coacting threaded stud 11. Thus it will be seen that by removing the wing nut 10, the frame member 4 may be raised or turned upon its pivot 5 in a manner that the film pan 3 may be removed from its bearing 2.

The film F as it is received from the projector (not shown) passes over the rotatable guide 12 mounted in the bearing 13, to the stationary, laterally deflecting guide 14, and thence over a similar guide 15, but reversely positioned relative to guide 14. The film then passes between the feed roller 16 and its coacting idler 17, said idler being provided with a bearing in its medial portion that is pivoted as at 18 to the frame member 4 and held in yielding engagement with the feed roller 16 by the coil spring 19, one end of which is secured to the frame member 4. The feed roller 16 is secured to the shaft 20 which is in axial alinement with the bearing 2. The said shaft 20 is rotatably mounted in and held against axial displacement by the bearings 21 forming part of the frame member 4. The lower end of the shaft 20 is rounded and rests upon a bearing plate 22 that in turn rests upon a yieldable member 23 herein shown as a helical compression spring resting upon the bottom of a recess 24 formed in the pan 3. Projecting from the center of the recess 24 in the pan 3 is a pintle 25 which is adapted to be received in the bearing 2 and form the bearing for the rotation of the pan 3. If desired, the adjusting screw 26 may be threaded into the bottom of the bearing 2 in a manner to limit the axial movement of the pintle 25.

By the arrangement of parts herein before stated, it is obvious that the film receiv-

ing pan will be yieldingly pressed downward when the frame member 4 is in normal position.

5 Positioned below the pan 3 and at right angles to its axis of rotation is the rotatable shaft 28, carrying the friction wheel 29, axially slidably, but rotatably fixed to said shaft. In the preferred embodiment of my invention I prefer to form this friction 10 wheel 29 with transverse ribs 29^a and also to cover the bottom of the pan 3 with rubber or other antislipping material 3^a in order that a better traction may be secured between these two elements.

15 The shaft 28 is suitably supported in the bearings 30 mounted on the base 1. Fixed to the shaft 28 is the bevel gear 31, which meshes with a bevel pinion 32 on the shaft 33 mounted in bearings 34 supported by the 20 standards 7; the other end of the shaft 33 is provided with a bevel gear 35 which in turn, meshes with a bevel gear 36 upon the shaft 5. Shaft 5 also has fixed to it a bevel gear 37 meshing with a bevel gear 38 upon 25 one end of a shaft 39 rotatably mounted in the frame member 4; the other end of shaft 39 is provided with a bevel gear 40 meshing with a bevel gear 41 secured to shaft 20. Thus it will be seen that as the pan 3 is rotated the feed roller 16 will be caused to operate in synchronism with it.

Since the film forms successive layers inwardly from the peripheral flange 27 of the pan 3 as the pan is rotated, it is obvious that 35 the film must be fed much faster when the reel of film is being started than when it is completed, or, in other words, the ratio of feed of the film to the speed of the pan must be greater at the beginning of the 40 winding than at the finishing thereof, and since in practice, the film is received to the device at a constant speed, the speed of the pan must therefore vary, so to this end, I provide a radially extending finger 42 upon 45 the pan 3, which will, upon rotation of the pan, coact with the star wheel 43 secured to the shaft 44, in a manner to rotate said shaft. Shaft 44 is rotatably mounted in a bearing 44^a secured to the base 1, and has 50 fixed thereto the worm 45. The friction wheel 29 is connected to a frame 46 slidably mounted upon shaft 28, in a manner as at 47^a, that the friction wheel may freely rotate on its shaft 28, but, will accompany said 55 frame 46 when axial movement is imparted to the frame. A face of the frame is provided with rack teeth 47 which are adapted to mesh with the worm 45. Thus it will be seen that upon rotating the star wheel 43 60 axial movement will be imparted to the friction wheel 29.

In the operation of my device, the film F is passed over guide 12 around the lateral deflecting guides 14 and 15, then between the

feed rollers 16 and 17, and secured to the 65 flange 27 of the pan 3 by means of a suitable clip or other fastening device 48. Power may be applied at any point of the rotating parts of my device, but I prefer to apply it to shaft 5, by means of any suitable prime 70 mover (not shown) causing the shaft to rotate the meshing gears 37 and 38, thus transmitting the rotation through shaft 39 and the gears 40 and 41 to the shaft carrying the feed roller 16, in turn, causing the film to 75 be fed continuously and at a constant speed to the receiving pan 3. The rotating of shaft 5 will also cause the gears 36 and 35 to rotate shaft 33, which in turn rotates gears 32 and 31, causing shaft 38, carrying 80 friction wheel 29, to revolve the pan 3. As the pan 3 rotates, the radially extending finger 42 will cause the star wheel 43 on shaft 44 to revolve step by step. The revolving of shaft 44 will in turn rotate the 85 worm 45 carried by it, and since the worm is normally in mesh with rack 47 on frame 46, the frame will be moved axially toward the center of pan 3, thus increasing the speed of the pan as the film is continuously 90 fed thereto.

When the winding operation is completed the wing nut 10 is removed from the stud 11, and the frame is swung outward away from the pan 3, relieving the tension of the 95 spring 23 and allowing the pan 3 to be removed from its bearing 2. As the frame 4 is swung on its pivot or shaft 5, it carries the cam 49 with it. This cam forces the push rod 50, mounted in guides 51 and pivoted at 100 one end to the rock arm 53 downwardly against the tension of the spring 52, and, by so doing, the outer end of the rock arm 53 also pivoted to the standard 7, is lowered. The outer end of rock arm 53 is provided 105 with the anti-friction roller 54 normally in contact with the frame 46 in a manner to keep the rack and worm in mesh, therefore, as the frame member 4 is swung on its pivot the rack 47 is allowed to be lowered by its 110 own weight, then the contractile spring 55 connected to the frame 46, and to one of the bearings 30, will immediately return to the friction wheel 29 carried by frame 46 to its original position, or, in a position for start- 115 ing the next winding operation.

I claim:—

1. In a film winding mechanism, a rotatable film receiving receptacle, a feeding means for the film, means for rotating the 120 receptacle and operating the feeding means, and means operated by said receptacle for increasing the speed of the receptacle relative to the feeding means.

2. In a film winding device, a rotatable 125 film receiving receptacle, means for rotating said receptacle and feeding the film to said receptacle, and means carried by said re-

- ceptacle coacting with a speed changing mechanism for changing the speed of said receptacle.
3. In a film winding device, a rotatable film receiving receptacle, means for feeding film to said receptacle, means for holding said receptacle in yielding contact with a friction roller whereby said receptacle is rotated.
- 10 4. In a film winding device, a rotatable film receiving receptacle, means for feeding film to said receptacle, means for holding said receptacle in yielding contact with a friction roller, whereby said receptacle is rotated, and means for moving said friction roller nearer the axis of rotation of said receptacle in a manner to increase the speed of said receptacle.
- 20 5. In a film winding device, a rotatable film receiving receptacle, means for constantly feeding film to said receptacle, a driving friction wheel for said receptacle in driving relation with said feeding means and means for moving said wheel nearer the 25 axis of rotation of said receptacle as said receptacle rotates in a manner to constantly increase the speed of said receptacle, and means carried by said receptacle for operating said wheel moving means.
- 30 6. In a film winding device, a rotatable film receiving receptacle, means for constantly feeding film to said receptacle, a driving friction wheel for said receptacle in driving relation with said feeding means, 35 a frame adapted to shift said wheel to and from the axis of said receptacle, a worm adapted to coact with a rack on said frame for moving said wheel axially, and means for rotating the worm as said receptacle revolves.
- 40 7. In a film winding device, a rotatable film receiving receptacle, means for constantly feeding film to said receptacle, a driving friction wheel for said receptacle in driving relation with said feeding means, 45 a frame adapted to shift said wheel to and from the axis of said receptacle, a worm adapted to coact with a rack on said frame for moving said wheel axially, and means 50 for rotating the worm as said receptacle revolves, said means comprising a star wheel in driving relation with the worm, and a finger on said receptacle coacting with said star wheel in a manner to rotate said worm.
8. In a film winding device, a rotatable film receiving receptacle, means for constantly feeding film to said receptacle, a driving friction wheel for said receptacle in driving relation with said feeding means, a frame adapted to shift said wheel to and 60 from the axis of said receptacle, a worm adapted to coact with a rack on said frame for moving said wheel axially, and means for moving said rack out of engagement from said worm.
- 65 9. In a film winding mechanism, a rotatable film receiving receptacle, a frame member positioned diametrically across said receptacle pivoted at one end and removably held at the other, a friction wheel in contact with said receptacle, means for controlling the axial position of said wheel, and means carried by said frame whereby when the same is swung upon its pivot the means for controlling the axial position of said wheel 70 will be rendered inactive.
- 75 10. In a film winding mechanism, a rotatable film receiving receptacle, a frame member positioned diametrically across said receptacle pivoted at one end and removably held at the other, a friction wheel in contact with said receptacle, means for controlling the axial position of said wheel, and means carried by said frame, whereby when the same is swung upon its pivot the means for controlling the axial position of said wheel 80 will be rendered inactive, and means for automatically returning said wheel to its original position when the axial controlling means is rendered inactive.
- 85 90 11. In a film winding mechanism, a rotatable film receiving receptacle, a frame member positioned diametrically across said receptacle pivoted at one end and removably held at the other, a friction wheel in contact with said receptacle, means for controlling the axial position of said wheel, and means carried by said frame whereby when the same is swung upon its pivot the means for controlling the axial position of said wheel 95 will be rendered inactive, and upon returning said frame to its original position said axial controlling means will again become active.
- 100 The foregoing specification signed at 105 Greenville, Ohio, this 9th day of March, 1916.

DAVID P. WHITESELL.
